DESIGN FOR A COMBINED CHIMNEY, LAMP SUPPORTING STRUCTURE, AND LAMPS

Clyde K. Lamb, Cleveland, Ohio

Application January 23, 1942, Serial No. 105,388

Term of patent 14 years

To all whom it may concern:

Be it known that I, Clyde K. Lamb, a citizen of the United States, residing at Cleveland, in the county of Cuyahoga and State of Ohio, have invented a new, original and ornamental Design for a Combined Chimney, Lamp Supporting Structure and Lamps, of which the following is a specification, reference being had to the accompanying drawing, forming a part thereof, in which:

Fig. 1 is an elevational view of the combined chimney, lamp supporting structure and lamps, showing my new design,

Fig. 2 is a sectional view thereof taken from the plane 2—2 of Fig. 1; and

Fig. 3 is a fragmentary view thereof in perspective, with the smoke stack omitted for convenience of illustration.

I claim:

The ornamental design for a combined chimney, lamp supporting structure and lamps, substantially as shown.

CLYDE K. LAMB.
